(57) **CLAIM**

The ornamental design for a tiki nutcracker, as shown and described.

DESCRIPTION

FIG. 1 is a front view of a tiki nutcracker showing my new design.

FIG. 2 front, side perspective view thereof.

FIG. 3 is a side view thereof; and,

FIG. 4 rear view thereof.

The broken line showing portion of a tiki nutcracker is included for illustrating environmental structure and forms no part of the claimed design.

1 Claim, 4 Drawing Sheets
